CLAIM

The ornamental design for a nebulizer, as shown and described.

DESCRIPTION

FIG. 1 is a perspective view of a nebulizer showing my new design with a portion in an extended configuration; FIG. 2 is a right side view in the extended configuration thereof;

FIG. 3 is a left side view in the extended configuration thereof;

FIG. 4 is a front view in the extended configuration thereof;

FIG. 5 is a rear view in the extended configuration thereof;

FIG. 6 is a top plan view thereof;

FIG. 7 is a bottom plan view thereof;

FIG. 8 is a perspective view of the nebulizer of FIG. 1 in a retracted configuration;

FIG. 9 is a front view in a retracted configuration thereof; and,

FIG. 10 is a rear view of the nebulizer in a retracted configuration thereof.

The broken lines in the drawings illustrate portions of the nebulizer that form no part of the claimed design.

1 Claim, 10 Drawing Sheets
